UNITED STATES PATENT OFFICE.

HAROLD D. MITCHELL, OF BROOKLYN, NEW YORK, ASSIGNOR TO SHEFFIELD CLARK, TRUSTEE, OF NASHVILLE, TENNESSEE.

DESIGN FOR A TIRE TREAD.

Application filed January 6, 1922. Serial No. 79. Term of patent 14 years.

To all whom it may concern:

Be it known that I, HAROLD D. MITCHELL, a citizen of the United States of America, residing at Brooklyn, in the county of Kings, city and State of New York, have invented a new, original, and ornamental Design for a Tire Tread, of which the following is a specification, reference being had to the accompanying drawing, forming a part thereof.

Figure 1 represents a plan view of the tire.

Figure 2 a cross section thereof.

A prominent feature of the design is the counter-sunk portion forming the letter **T** in combination with the raised portion forming the block letter **C**.

What I claim is:

The ornamental design for a tire tread as shown, and described.

HAROLD D. MITCHELL.
